(57) **CLAIM**

The ornamental design for a plant root watering device, as shown and described.

DESCRIPTION

FIG. 1 is a perspective view of a plant watering device showing our new design, the broken lines representing environmental structure are for illustrating purposes only, forming no part of the claimed design. It is understood that the in-ground portion of the claimed design is fully disclosed in FIGS. 2-6;

FIG. 2 is a perspective view thereof.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a bottom plan view thereof; and,

FIG. 8 is a top plan view thereof.
